(57) **CLAIM**

The ornamental design for a wall panel, as shown.

DESCRIPTION

FIG. 1 is a front perspective view of a wall panel;

FIG. 2 is a rear view of the wall panel;

FIG. 3 is a right side view of the wall panel;

FIG. 4 is a bottom view of the wall panel; and,

FIG. 5 is a top view of the wall panel.

The dotted lines showing of support braces and adjacent wall panels is provided for environmental purposes only and forms no part of the claimed design.
